(57) **CLAIM**

The ornamental design for a constant velocity joint coupling flange, as shown and described.

DESCRIPTION

FIG. 1 is a perspective view, of the rear side of a constant velocity joint coupling flange, showing my new design;

FIG. 2 is a perspective view of the front side, thereof;

FIG. 3 is a front elevational view, thereof;

FIG. 4 is a rear elevational view, thereof;

FIG. 5 is a side elevational view, the opposite side elevational view being substantially a minor image thereof; and,

FIG. 6 is a side elevational view taken to a reduced scale, the broken line representations of the automotive transfer case, the drive line, and the differential being shown solely for illustrative purposes, forming no part of the claimed design.
